1 Claim. (Cl. 83—321)

This invention relates to thread cutting devices.

As a rule, webs or sheets of different materials, notably paper, are cut by means of threads either in a flat-operating high-power press, or with the assistance of a cylinder or an oscillating bed rolling without sliding on the cutting form or pattern.

In either case the presser member must be relieved to permit the feeding of the web or sheet to be cut, together with intermittent control means producing inertia stress attaining in many cases considerable values whereby the rate of operation of the machine must be reduced.

Rotary cutting devices are also known wherein the cutting unit comprises two cylinders, one cylinder carrying cutters or blades cutting by pressure on the other cylinder constituting the counterpart. These devices are costly and fragile for the threads are machined directly in the cylinder material. When the threads are worn or damaged the complete cylinder has to be replaced. On the other hand, this rotary cutting device is capable of operating at relatively high speeds because the inertia of the moving members is very low.

On the other hand, sheet printing devices are also known wherein the printing blocks are moved in planes parallel to themselves along a closed path comprising two parallel rectilinear portions interconnected at their ends by two curved sections. During their movement, the printing blocks travel through the gap formed between a printing cylinder and a counter-pressure cylinder, the sheets to be printed being carried along around the periphery of the presser cylinder.

It is the object of this invention to provide a thread-type cutting device operating according to the basic principle of the printing apparatus of the type mentioned in the preceding paragraph, but designed for cutting continuous webs.

To this end, this invention provides a device for cutting a continuous web by means of threads, this device being characterized in that it comprises in combination means for moving along a closed curvilinear and rectilinear path flat cutting blocks provided with cutting threads, and for maintaining these blocks parallel to themselves during their travel, whereby they move between a presser cylinder and a counter-pressure cylinder, and means actuated intermittently for holding the web against motion when no block is present in proper cutting position between said cylinders, and on the contrary releasing said web when a cutting block is engaged between said cylinders.

The device according to this invention is advantageous in that the manufacture of the cutting blocks is relatively simple, notably through the use of cutting threads inserted in a wooden or like block. The cost of these blocks is therefore very low.

On the other hand, as the cutting blocks travel continuously, no sudden variation in the inertia of the moving component elements can take place.

In order to afford a clearer understanding of the present invention and of the manner in which the same may be carried out in practice, reference will now be made to the accompanying drawings illustrating diagrammatically by way of example a typical embodiment of a device con-

2

structed according to the teachings of the invention. In the drawings:

FIGURE 1 is a longitudinal section showing the device during the cutting of a web.

5 FIGURE 2 is a longitudinal section similar to FIG. 1 but showing the device between two cutting steps, the web feed device being omitted from this figure.

10 FIGURE 3 is a simplified elevational view showing the different component elements of the kinematic arrangement.

FIGURE 4 is a cross section taken upon the line IV—IV of FIG. 1.

FIGURE 5 is a cross section taken upon the line V—V of FIG. 1.

15 FIGURE 6 is a cross section taken upon the line VI—VI of FIG. 1.

The device according to this invention comprises a frame structure 1 consisting essentially of a pair of side plates. The cutting blocks designated generally by the 20 reference numeral 2 have a substantially flat configuration and comprise a plate 2a carrying a bed plate 2b adapted to receive the threads 2c. Each block 2 is secured on a pair of lateral racks 3, 4 having their teeth cut in the upper and lower faces as shown at 3a, 3b and 25 4a, 4b respectively. Racks 3, 4 are interconnected through a pair of cross members 5 so as to constitute a rigid frame and rigid with lateral guide members 38.

These racks 3, 4 are driven by pinions 6 during the rectilinear portion of the travel of the cutting blocks 2. 30 These cutting blocks are also driven along curved paths, while remaining parallel to each other, by three pairs of notched wheels 7, 8 and 9; each wheel 7—9 has formed therein a pair of notches 7a, 8a, 9a spaced 180° from each other. The pair of wheels 7, 9 are disposed symmetrically in relation to the axis of the pair of central wheels 8.

35 The aforesaid pinions 6 are rigid with shafts 10 rotatably driven from the main power shaft 11 of the machine (see FIG. 3) through trains of gears 12, 13, 14, 15, 16, 17, 6a on the right-hand side, and 12, 13, 14, 15, 18, 20, 6a on the left-hand side.

40 The right-hand and left-hand notched wheels 7, 9 are rotatably mounted in overhanging relationship on spindles 21 rigid with the frame structure 1 of the machine in order to free the passage for the cutting blocks 2 during their movement of rotation. The notched wheels 7, 9 are rigid with pinions 22 and rotatably driven from the power shaft 11 (FIG. 3) through trains of gears 12, 13, 14, 15, 16, 17, 23, 22 for the right-hand wheel 7, and 12, 13, 14, 15, 18, 20, 24, 22 for the left-hand wheel 9.

45 The two central wheels 8 are rotatably mounted on hollow spindles 25 rigid with the frame structure 1. They are rigid with pinions 19 and rotatably driven from the power shaft 11 through trains of gears 12, 13, 14, 15, 16, 17, 18a and 19.

50 The racks 3 and 4 carry each at their two longitudinal ends a pair of rollers 26, 29 journaled on a common shaft and, substantially intermediate their ends, a roller 29a located in the same longitudinal plane as the rollers 29.

55 The racks 3 and 4 are rotatably driven through the rollers 26 engaging the notches 7a, 8a, 9a of the notched wheels 7, 8, 9.

60 A central switching device is provided for assisting the rollers 26 in their driving engagement with the notches 8a of the central wheel 8 to ensure the movement of rotation, or permitting the passage, of these rollers 26 for the rectilinear block movement. This device 65 comprises a pair of movable upper guide members 27 and a pair of movable lower guide members 27a. These

guide members are pivoted on pins 28 and 28a respectively.

The upper movable guide members 27 and lower movable guide members 27a are interconnected through links 70. Each upper movable guide member 27 is rigid with a driven toothed segment 80 in meshing engagement with a driving toothed segment 71 rigid with a cross shaft 72. This shaft 72 and therefore the guide members 27 and 27a are pivoted by cam means 73, 73a rotatably driven about the pin 74 by a pinion 75 meshing with the aforesaid pinion 16. To this end the shaft 72 has keyed thereon a sleeve 76 having a pair of arm extensions 77, 78 carrying followers in the form of rollers 79 and 80 bearing on cams 73 and 73a.

The racks 3 and 4 are guided in the longitudinal direction by rollers 29 and 29a disposed between the upper rails 30 and the central rails 31, 32, 33, 34 at the upper portion and between the lower rails 35 and central rails 31, 32, 33, 34 at the lower portion during the rectilinear travel.

During the movement of rotation (see FIG. 2) the racks are guided by curved rails 36 at the two longitudinal ends of the raceway.

The racks 3, 4 are guided in the transverse direction by rollers 37 journaled on pins carried by the upper rails 30 and lower rails 35, engaged by the lateral guide members 38 rigid with racks 3 and 4.

The cutting blocks 2 secured on racks 3, 4 travel through the gap left between the cylinders 39 and 40. The lower or presser cylinder 39 is rigid with the power shaft 11 and revolves at a constant angular speed.

The peripheral speed of this cylinder 39, which has a diameter equal to the pitch diameter of pinion 12, equals the linear speed of racks 3, 4 and therefore the velocity of translation of the cutting blocks 2. The developed or peripheral length of cylinder 39 equals the distance between the axes of the right-hand and left-hand notched wheels 7, 9, plus the length of the circumference at the pitch circle of a toothed wheel, this pitch circle having a diameter corresponding to half the distance between the wheels 7 and 9 and to the diameter of the pitch circle of pinions 19 and 22. The central wheel 8 is equally spaced from wheels 7 and 9.

The upper or counter-pressure cylinder 40 is rigid with pinion 15 and rotatably driven from the power shaft 11 through a train of gears 12, 13, 14, 15 the pitch circle of pinion 15 having the same diameter as said cylinder 40. Thus the latter is driven at a peripheral speed equal to that of cylinder 39 and also to the linear speed of the cutting blocks 2.

The vertical position of shaft 11 may be altered through any suitable means to permit the adjustment of the gap left between cylinders 39 and 40 as a function of the thickness of the cutting blocks 2.

To this end the shaft 11 may be carried, as shown, by eccentric sockets 41, 42 held against motion in the position corresponding to the desired gap between cylinders 39 and 40. Of course, any other suitable means may be used for varying the vertical position of shaft 11.

The web 43 to be cut is delivered in a predetermined size by a pair of feed cylinders 44, 45 revolving at a constant angular speed and imparting therefore a constant linear speed to the web, this speed being in any case constantly lower than the linear speed of the thread cutting blocks 2.

The device comprises on the other hand two pairs of web-receiving cylinders, that is, cylinders 46, 47 on the one hand and cylinders 48, 49 on the other hand. The shafts 46a and 48a of the lower cylinders 46 and 48 (FIG. 3) are rigid with pinions 50 and 51, respectively, and the diameter of these cylinders is equal to the pitch diameter of these pinions. Cylinder 46 is rotatably driven from the main power shaft 11 through the train of gears 12, 52, 50. Cylinder 48 is rotatably driven from the left-hand wheel 9 through the train of gears 75

22, 53, 54, 51. The upper cylinders 47 and 49 are carried by arms 55 and 56, respectively, these arms being pivoted on the frame structure 1 of the device by means of pins 55a and 56a, respectively. The web receiving cylinders 46, 47, 48, 49 revolve at a peripheral speed equal to the linear speed of cutting blocks 2, due to the transmission ratios obtaining between the pinions.

The device further comprises, on the web feed side, a set of clip arms 57 pivoted on a pin 58 carried by the frame of the device. These clip arms 57 are adapted to either engage a tray 59 over which the web 43 is caused to slide, or be moved away therefrom.

The movement of these clip arms 57 is controlled cyclically through any suitable means, whether of mechanical, pneumatic, electronic or electric type, in order to discontinue the feed movement of web 43 through the apparatus during the time intervals in which no cutting block 2 is fed between the cylinders 39 and 40. In the specific form of embodiment illustrated, the movement of clip arms 57 is controlled by a pair of cams 60, 61 mounted on a shaft 62 rigid with pinion 52 having a pitch diameter equal to half that of pinion 12. These cams 60, 61 are engaged by a roller follower 63 carried by the end of an arm rigid with shaft 58.

Each cam 60, 61 comprises a segment of smaller diameter and a segment of greater diameter, and they are adapted to be shifted angularly from each other. Thus, the time period during which the clip arms 57 release the web 43 can be varied at will, that is, as a function of the paper size contemplated.

The device according to this invention operates as follows:

As long as no cutting block 2 is in its operative position between the cylinders 39 and 40 (that is, when the blocks 2 are rotating) the clip arms 57 hold the web 43 against longitudinal motion. During the initial portion of the block translation, when the first cutting block engages the gap left between the cylinders 39 and 40, and the cutting threads of this block engage the presser cylinder 39, the cams 60, 61 set for this purpose cause the rotation of lever 64 to raise the clip arms 57 off the web. Thus, the latter is free to move at the desired linear speed through the device. This is permitted by the fact that the web 43, which is held against motion during the rotation of blocks 2, develops a loop 43a of variable length between the feed cylinders 44, 45 and the first pair of web-receiving cylinders 46, 47. This loop increases when the clip arms 57 discontinue the delivery of web to the cutting device, and decreases when the clip arms are raised. In principle this loop 43a is never taken up completely.

Each cutting block travels between the cylinders 39 and 40 to cut the web to the required dimensions. When the cutting block has completed its rectilinear stroke through the gap between cylinders 39 and 40, cams 60 and 61 become operative to drop the lever 64 and therefore hold the web against motion through the clip arms 57.

Then the loop 43a increases again, the clip arms 57 holding the web 43 until the next cutting block is positioned for accomplishing its rectilinear stroke.

After having been cut by the threads on the cutting blocks, the web is fed to a rotary decorticating or like device of known type (not shown).

Of course, the specific form of embodiment shown hereinabove with reference to the accompanying drawings should not be construed as limiting the invention as it is given by way of example only; thus, many modifications and alterations may be brought thereto without departing from the spirit and scope of the invention as set forth in the appended claim.

What I claim is:

A device for cutting a continuous web by means of threads, which comprises in combination a power shaft, a presser cylinder and a counter-pressure cylinder disposed parallel to each other so as to leave a constant gap therebetween, means for continuously rotatably driving

said presser and counter-pressure cylinders from said power shaft, at least one flat thread-carrying cutting block, means driven from said power shaft for moving said flat cutting block unidirectionally along a closed curved path and through said gap while keeping said block parallel to itself during its travel through said gap, means for feeding said web into said gap between said cylinders a stationary bed plate over which said web is caused to slide in advance of said gap, a pin extending transversely to the direction of feed of said web, a clip arm pivoted on said pin and adapted to engage said bed plate, and means controlled cyclically from said power shaft for lowering said clip arm toward said bed plate until said cutting block begins to travel through said gap between said presser cylinder and said counter-pressure cylinder for the purpose of gripping said web between said clip arm and stationary

bed plate and thereby holding said web against motion and subsequently raising said clip arm when said block engages said gap.
